UNITED STATES PATENT OFFICE.

MARIUS RATIGNIER AND MARIUS CLERC-RENAUD, OF LYONS, FRANCE.

MACHINE FOR TENTERING AND DRYING FABRICS.

SPECIFICATION forming part of Letters Patent No. 764,254, dated July 5, 1904.

Application filed September 15, 1903. Serial No. 173,328. (No model.)

To all whom it may concern:

Be it known that we, MARIUS RATIGNIER and MARIUS CLERC - RENAUD, citizens of France, residing at 61 and 63 Rue Louis Blanc, 5 Lyons, France, have invented new and useful Improvements in Machines for Tentering and Drying Fabrics, of which the following is a specification.

This invention relates to the device forming the subject-matter of the invention described in Letters Patent of the United States granted to us on May 5, 1903, No. 727,443.

The present invention has for its object certain arrangements which insure the regular working of tentering and drying machines, in which the tentering is obtained by drawing the fabric forward by parallel chains undulated in a horizontal plane, such as described in the patent above mentioned. These arrangements, which relate to the good management of the fabric, are illustrated by the accompanying drawings, which represent diagrammatically the progress of the fabric.

Figure 1 is a longitudinal section, and Figs. 5 2 and 3 plans, of the apparatus.

The tentering apparatus consists of two parallel chains, as described in the patent above mentioned, on which the two edges *a a* of the fabric are fixed by nippers. These chains are guided by rollers *b b b' b'* and follow an undulated course without ceasing to be parallel. It therefore results that the weft-threads *c c*, Fig. 2, preserve the same length in the straight part and in the sinuous part of their travel on condition nevertheless that they remain perpendicular to the main axis of the machine. This condition cannot always be fulfilled. Certain fabrics are presented to tentering with very irregular wefts, and it will be understood that if the weft is presented obliquely, as at *c' c'*, in the sinuous part of the course it might undergo lengthenings sufficiently great to bring about breakage. To prevent this inconvenience, we 5 arrange the set of pulleys *b b* on one side of the fabric movable in the longitudinal direction. These pulleys are for this purpose carried by a slide *d*, which can be put in motion in either direction by means of a hand-wheel *e* acting on a rack, a screw, or other suitable mechan-

ism. An attendant placed near this hand-wheel watches the passage of the fabric and during its progress moves in one direction or the other the set of pulleys *b b*, according to the obliquity of the weft. This motion (see 55 Fig. 3) has the effect of preserving as much as possible the same length to the oblique weft-threads *c' c'* while they transverse the sinuous parts of the course, and consequently prevents tearing of the fabric. 60

The tension of the weft-threads which permits of obtaining the best tentering without risk of tearing the fabric requires, to obtain it, that their length be varied at each instant. On the contrary, the definitive width obtained 65 of the fabric during drying should generally be constant. To enable these two conditions to be realized, we give the set of pulleys *b b'* a second motion in the transverse direction of the fabric. This motion is obtained by a 70 screw *k* or other suitable means and is effected at a convenient moment by the same attendant who controls the longitudinal motion.

While the fabric is traversing the sinuosities producing the tentering its different elements retain risks of tearing, which are maximum when the weft and warp threads form the greatest angle with each other. We diminish these risks of tearing by slightly reducing the length of the weft-threads at the 75 moment when they pass into the dangerous parts above indicated. For this purpose the pulleys have slight differences of diameter. The larger pulleys *b' b'* are situated at the outside of the selvages *a a* of the fabric. It results from this arrangement that in positions such as *c*, Fig. 2, where the weft is inclined 80 on the warp, this weft is a little shorter than when it is normal to the warp, as at *c' c'*. 85

During the undulated progress of the fabric the central part of the latter follows the same sinuosities as the selvages gripped in the chains consequent on the pull of the weft-threads. This pull is converted into a tension of these threads, which is maximum at one of their ends, which decreases according to their length and which is greater in proportion as the fabric itself is more stretched in the direction of its length. 90

In order to reduce as much as possible this 100

increase of tension of the weft-threads, which might be dangerous during the tentering, it is also necessary, therefore, to reduce as much as possible the tension of the fabric in the direction of its length during tentering. On the other hand, during the drying the fabric generally requires to be stretched in every direction. The longitudinal tension of the fabric during the tentering is with this object maintained sufficiently low; but as this same fabric should be more highly stretched during the drying we place before the drying-drum *f*, or before drying apparatus of any form which follows the tentering, rollers, such as *h h' r r'*, which serve for this purpose.

We would remark that the details employed in carrying our invention into effect may be varied without departing from the peculiar character thereof.

What we claim as our invention, and desire to secure by Letters Patent, is—

1. In a tentering and drying machine, tentering-chains for conducting the fabric, two sets of pulleys producing an undulating progress of the chains, the pulleys of each set which are placed in the interior of the tenter-

ing-chains, having a smaller diameter than the pulleys placed on the exterior thereof, in order to reduce the length of the weft while the warp-threads are the most inclined.

30

2. In a tentering and drying machine the combination with tentering-chains, of two sets of pulleys to produce an undulating progress of the tentering-chains, and means for moving by hand one of the sets in both a longitudinal and transverse direction.

3. In a tentering and drying machine the combination with tentering-chains, of two sets of pulleys one set of which is regulable transversely and longitudinally, and rollers holding the fabric after the tentering, said rollers having their axes at right angles to the axes of the pulleys.

In testimony whereof we have signed our names to this specification in the presence of two subscribing witnesses.

MARIUS RATIGNIER.
MARIUS CLERC-RENAUD.
